(57) **CLAIM**

The ornamental design for a display screen or portion thereof with transitional graphical user interface, as shown and described.

DESCRIPTION

FIG. 1 is a front view of a display screen or portion thereof with a transitional graphical user interface showing a first image of the claimed design; and,

FIG. 2 is a second image thereof.

The outermost evenly spaced broken lines show an electronic device that forms no part of the claimed design. The dot-dash broken lines show a display screen or portion thereof and form no part of the claimed design. The remaining broken lines and all lined-through text, show portions of the transitional graphical user interface, and form no part of the claimed design.

The appearance of the transitional image sequentially transitions between the views of FIGS. 1-2. The process or period in which an image transitions to another forms no part of the claimed design.
